CELLULAR EGG CARTON

Louis Schwartzberg, Chicago, Ill.

Application August 8, 1942, Serial No. 454,176

4 Claims. (Cl. 229—28)

My present invention relates to improvements in cellular egg cartons.

It is now generally and definitely known that, with the various designs of egg cartons available, it is necessary to employ material for their construction of not less than a certain thickness in order to secure requisite protection for the eggs. The material generally employed, known to the trade as straw-board, is sold for so much per ton, and a ton of such material of a definite thickness will permit of making of only so many cartons of the same design. A change of thickness of several points, as the gauge or measure of thickness is usually referred to, results in securing several thousand more or less cartons from a ton of material.

It is the object of my present invention to provide a cellular egg carton which may be made of a thickness of material heretofore regarded as too thin to afford necessary strength, and which will, nevertheless, result in the provision of a carton affording to the eggs greater protection against breakage than cartons hitherto formed from much thicker material. I am able to attain this object by a clear perception that, in the absence of an accident which would render any carton ineffective, the only places where protection is effective with eggs are the ends upon which they rest and their bellies. The protecting and cushioning effect of a plurality of contiguous layers at the lower ends and bellies of the eggs is enhanced by slitting through the folded edges at intervals between locations for transverse and longitudinal parts forming inner cell walls.

I attain my object by means of the structure illustrated in the accompanying drawings in which—

Fig. 1 is a development or blank, before folding, of which my carton, with the exception of the central longitudinal partition, is formed;

Fig. 2 is a transverse section showing the relations of the longitudinal portions of the development or blank after the same has been folded;

Fig. 3 is a longitudinal, vertical section showing the disposition of the transverse partitions after folding; and

Fig. 4 is a front elevation of the central longitudinal partition.

Similar reference characters refer to similar parts throughout the respective views.

In order to secure a clear understanding of the relation of the parts or areas of the development or blank to their location and the functions they perform in the folded carton, which is vital in producing the present structure, par-

ticular reference should be made to Figs. 1 and 2. The area designated 5 at one end of the development or blank, which is cut to provide the laterally extending tongues or tangs 6, comprises an attaching flap for releasably securing in place the cover of the carton. Creased to extend at substantially right angles thereto is the area 7 providing the cover of the carton. Adjacent to the cover 7 and creased at the juncture therewith so as to permit the cover to hinge, is the back 8. Adjacent thereto and folded to extend at right angles therewith is the bottom 9. Arising from the bottom 9 is the front 10 and this is of slightly less height than the back 8. Folded to extend closely adjacent to and parallel with the upper portion of the front 10 is a strip 11 which serves to locate the lower false bottom 12 a desired distance below the top edge of the front 10. Upwards from the opposite edge of the lower false bottom layer 12 extends a strip 13 which is the same in height as the strip 11 and serves to locate the carton top 14, level with the top edge of the front 10. From the top 14 are provided the cross or transverse partitions, designated from 15 to 21 respectively, for forming the ends of the carton, and pairs of egg cells as hereinafter described. A strip 22 is connected to, and extends downwards from, the front margin of the top 14. This strip, as shown in Figure 2, is positioned opposite the strip 11. A second false bottom 23 is connected to, and projects rearwards from, the bottom margin of the strip 22 and overlies, and is the same in size as, the false bottom 12.

The cross or transverse partitions, 15 to 21 inclusive, connect only with the remainder of the top 14 by means of the triangular hinge portions 24, and it will be noted that these hinge portions are located so that the line upon which the hinging occurs requires the partitions to be folded upon themselves and doubles the layers in the walls of the cross or transverse partitions to a point below the bellies of the eggs. Slots 25 extending across the hinging lines in the cross or transverse partitions, are provided for permitting the entry of and locating the longitudinal partition member 26.

Slits 27 are made on both sides of the cross slots 25 in the fold lines of the cross or transverse partitions 15 to 21 inclusive and at intervals on the fold line between the front 10 and the strip 11, as such slits have been found to add substantially to the cushioning effect upon the eggs of plural cell walls.

The two layers of the material at the back of the cell portion of the carton and also the oppo-

site three layers of material at the front of the carton may be secured together by adhesive or any other desired way, but it is suggested that the securing be only done at intervals as these walls or layers are more than ordinarily strong and the securing of them together continuously impairs their cushioning effect upon the eggs.

The slot 28 in the lower edge at the left end of the central longitudinal partition 26 is sufficiently deep to accommodate the left end cross partition 15 of the carton, but the similar slots 29 are shorter so that the central longitudinal partition 26 enters the slots 25 in cross partitions 16 to 21 inclusive. The lower portion of the central longitudinal partition, between the slots 28 and 29, is developed into lateral tongues or tangs 30 which enter the apertures 31 provided centrally of the false bottoms 12 and 23 and serve as additional holding and supporting means for the false bottoms.

The central longitudinal partition 26, supported as it is through engagement at frequent intervals with the cross partitions 15 to 21 inclusive, extends from the inner surface of the bottom 9 to the inner face of the cover 7, and affords in itself sufficient strength to support what additional weight might, from time to time, be placed on the carton.

I have also shown two rows of Roman key slots 32 in the false bottoms 12 and 23 which may be employed, if desired, further to increase the cushioning effect of the support for the eggs, but which are hardly necessary in view of the formation of the double thickness of the bottom structure.

It will now be seen that I have provided a cellular egg carton in which the cellular portion of the structure is provided with a double layer back portion, a triple layer front portion and a double layer false bottom for supporting the eggs, which affords greater strength and cushioning effect than cartons heretofore made from much thicker material. Special advantages accrue from the triple layer front portion as it is at this point that most manipulation occurs in engaging and disengaging the tongues or tangs 6 with and from the triangular hinge portions 24. It will also be observed that there is substantially no waste of material in the formation of the development or blank.

Having described my invention, what I claim as new and desire to secure by Letters Patent is—

1. An egg carton comprising an elongated blank of thin straw board folded transversely on spaced apart parallel lines to provide a cover with a depending attaching flap along its front margin, a back connected to, and depending from, the rear margin of the cover, a bottom connected to, and extending forwards from, the bottom margin of the back and disposed at right angles to said back, a front connected to, and extending upwards from, the front margin of the bottom and disposed in parallel relation with the back, a first strip of less height than the front connected to, and extending downwards from the top margin of the front and fitting against the inner surface of the upper portion of said front, a first false bottom of substantially the same size as the bottom connected to, and extending rearwards from the bottom margin of said first strip and disposed above and in parallel relation with the bottom, a second strip of substantially the same height as the first strip connected to, and extending upwards from, the rear margin of the first false bottom and fitting against the inner surface of the

upper portion of the back, a top of substantially the same size as the first false bottom connected to, and extending forwards from the top margin of the second strip and disposed above and in parallel relation with said first false bottom, a third strip of substantially the same height as the first strip, connected to, and extending downwards from, the front margin of the top and fitting against the inner surface of said first strip, and a second false bottom of substantially the same size as the first false bottom connected to, and extending rearwards from, the bottom margin of the third strip and directly overlying said first false bottom, said top being provided with a longitudinal series of three-sided slits in order to form transverse partitions and having the partitions bent downwards to form cells therebetween for eggs.

2. An egg carton comprising an elongated blank of thin straw board folded transversely on spaced apart parallel lines to provide a cover with a depending attaching flap along its front margin, a back connected to, and depending from, the rear margin of the cover, a bottom connected to, and extending forwards from, the bottom margin of the back and disposed at right angles to said back, a front connected to, and extending upwards from, the front margin of the bottom and disposed in parallel relation with the back, a first strip of less height than the front connected to, and extending downwards from the top margin of the front and fitting against the inner surface of the upper portion of said front, a first false bottom of substantially the same size as the bottom connected to, and extending rearwards from the bottom margin of said first strip and disposed above and in parallel relation with the bottom, a second strip of substantially the same height as the first strip connected to, and extending upwards from, the rear margin of the first false bottom and fitting against the inner surface of the upper portion of the back, a top of substantially the same size as the first false bottom connected to, and extending forwards from the top margin of the second strip and disposed above and in parallel relation with said first false bottom, a third strip of substantially the same height as the first strip, connected to, and extending downwards from, the front margin of the top and fitting against the inner surface of said first strip, and a second false bottom of substantially the same size as the first false bottom connected to, and extending rearwards from, the bottom margin of the third strip and directly overlying said first false bottom, said top being provided with a longitudinal series of three-sided slits in order to form transverse partitions and having the partitions bent downwards to form therebetween cells for eggs, said first and second false bottoms having apertures therein disposed mid-way between the front and rear margins thereof and between the partitions, and a longitudinal partition disposed mid-way between, and in parallel relation with, the back and front, provided with downwardly facing notches for accommodating the cross partitions, and having the portions thereof between the notches extending through and interlocked with the apertures and resting on the bottom.

70 3. An egg carton comprising an elongated blank
of thin straw board folded transversely on spaced
apart parallel lines to provide a cover with a
depending attaching flap along its front margin, a
back connected to, and depending from, the rear
margin of the cover, a bottom connected to and

extending forwards from, the bottom margin of the back and disposed at right angles to said back, a front connected to, and extending upwards from, the front margin of the bottom and disposed in parallel relation with the back, a first strip of less height than the front connected to, and extending downwards from the top margin of the front and fitting against the inner surface of the upper portion of said front, a first false bottom of substantially the same size as the bottom connected to, and extending rearwards from the bottom margin of said first strip and disposed above and in parallel relation with the bottom, a second strip of substantially the same height as the first strip connected to, and extending upwards from, the rear margin of the first false bottom and fitting against the inner surface of the upper portion of the back, a top of substantially the same size as the first false bottom connected to, and extending forwards from the top margin of the second strip and disposed above and in parallel relation with said first false bottom, a third strip of substantially the same height as the first strip, connected to, and extending downwards from, the front margin of the top and fitting against the inner surface of said first strip, and a second false bottom of substantially the same size as the first false bottom connected to, and extending rearwards from, the bottom margin of the third strip and directly overlying said first false bottom, said top being provided with a longitudinal series of pairs of transversely extending oppositely positioned three-sided slits, having the portions thereof within the slits folded downwards to form double thickness transverse partitions, and embodying transverse slits in the partitions fold lines.

4. An egg carton comprising an elongated blank of thin straw board folded transversely on spaced apart parallel lines to provide a cover with a depending attaching flap along its front margin, a back connected to, and depending from, the rear margin of the cover, a bottom connected to, and extending forwards from, the bottom margin of the back and disposed at right angles to said back, a front of less height than the back connected to, and extending upwards from, the

front margin of the bottom and disposed in parallel relation with the back, a first strip of less height than the front connected to, and extending downwards from the top margin of the front and fitting against the inner surface of the upper portion of said front, a first false bottom of substantially the same size as the bottom connected to, and extending rearwards from, the bottom margin of said first strip and disposed above and in parallel relation with the bottom, a second strip of substantially the same height as the first strip connected to, and extending upwards from, the rear margin of the first false bottom and fitting against the inner surface of the upper portion of the back, a top of substantially the same size as the first false bottom connected to, and extending forwards from the top margin of the second strip and disposed above and in parallel relation with said first false bottom, a third strip of substantially the same height as the first strip, connected to, and extending downwards from, the front margin of the top and fitting against the inner surface of said first strip, and a second false bottom of substantially the same size as the first false bottom connected to, and extending rearwards from, the bottom margin of the third strip and directly overlying said first false bottom, said top having a longitudinal series of three-sided slits therein in order to form transverse partitions and having the partitions bent downwards to form egg receiving cells therebetween, said first and second false bottoms having longitudinal elongated apertures therein disposed midway between the front and back margins thereof and between the partitions, and a longitudinal partition disposed midway between, and in parallel relation with, the front and back, provided with downwardly facing notches for accommodating the cross partitions, having the portions thereof between the notches extending through, and interlocked with, the apertures and resting on the bottom, and embodying upper edge portions coplanar with the upper edge of the back and serving to support the cover when the latter is in its closed position.

LOUIS SCHWARTZBERG.
